WARNING SIGNAL FOR FLUID BRAKES

Robert B. MacDonald, Hagersville, Ontario,
Canada

Application June 17, 1952, Serial No. 294,030

3 Claims. (Cl. 200—84)

1

This invention relates to improvements in warning signals of the kind which cause the operator of a motor vehicle to become immediately conscious of a drop in the level of the brake fluid in the reservoirs of the master cylinders of fluid braking systems beyond the maximum required for safety. More particularly the invention contemplates an improved switch for automatically closing an electric circuit, whereupon a signal, which may be either a visible or an audible signal, becomes energized when the fluid by reason of any of the common causes reaches a lower level than that which has been predetermined a safe level.

The invention consists essentially of a switch box mounted externally of the reservoir, the circuit closing element of which is loosely connected to the upper end of a plunger vertically reciprocal in the sleeve of a certain swivel, the plunger extending internally of the reservoir where it is pivotally connected to the arm of a float, the arm being also pivotally connected to a certain portion of the swivel which also extends into the reservoir.

Different makes of motor vehicles have differently proportioned brake fluid reservoirs, varying particularly in the diameters of their filling openings and plugs, the smallest being approximately seven-eighths of an inch. In reservoirs having wide openings it has been an easy matter to insert, or install, one of the common types of float operated switches, but such has not been true with reservoirs having the smaller openings, obviously because of the bulky character of those elements of the accessory which have to be inserted through the opening and disposed inside the reservoir.

An important object of the invention is to provide a float operated switch, the float and the float components of which may be easily introduced through the smallest known filling openings of brake fluid reservoirs.

Another important object is to provide means whereby, regardless of the rotary position of the switch box, that is, no matter where the switch box happens to stop when screwed home into the filling opening, the float and the float arm will be aimed or located in their proper place and will not become damaged in any way by the turning of the switch box.

Another important object is to provide novel means whereby establishment of even contact between the circuit closing element and certain terminal posts is assured, regardless of structural fault and the variance of the axis of the plunger off vertical.

2

A fourth important object is to provide a device of the kind specified which is manufactured in a single unit that is, with no separable parts, and so may replace the conventional filling opening plug simply by screwing out the one and screwing in the other.

A fifth important object is to provide a device of the class described which will be simple, durable, effective, and inexpensive to produce.

These together with other objects which may later appear may be attained by the structure and combination of parts which will be hereinafter fully described, specifically claimed, and illustrated in the accompanying drawings in which like reference characters refer to like parts throughout the several views and in which:

Figure 1 is a partial sectional elevation of a device as constructed in accordance with this invention, the adjacent portion of the fluid reservoir being partially shown and also in section.

Figure 2 is a reduced sectional elevation of a typical fluid reservoir showing the switch unit in the position of being introduced into place.

Figure 3 is an enlarged detailed elevation of the circuit closing element and the upper portion of the plunger.

Figure 4 is an enlarged top view of the circuit closing element.

Figure 5 is a cross-sectional elevation taken on the line 5—5 of Figure 4.

Referring now to the drawing, the fluid reservoir is indicated by R, its filling opening by RA.

In its present embodiment the invention consists of a switch box in the form of a cup 10 which preferably has flat opposed external faces, here shown as a hexagon, for receiving a wrench. The cup is extended downwardly in a reduced externally threaded base 12, which may well be termed a plug portion, which replaces the original plug in the filling opening when the switch is installed.

The cup 10 is closed by means of a disc 13 of insulation (non-conductive) material, and extending through this disc from the outside to the inside of the cup are spaced electric terminal posts 14. In practice, wires (not shown) are connected to these posts and lead through a power source (not shown) to an alarm or signal (not shown) which may be conveniently located within the vision or earshot as the case may be, of the vehicle operator.

A swivel consisting of a sleeve 15, which is preferably thimble-like, journaled in an opening 16 in the base portion 12, and a yoke 17 beneath and carried by the sleeve, is adapted to remain stationary while the cup turns when being screwed

into the reservoir. Through the sleeve 15 extends a plunger 18, on the upper end of which is provided a pair of collars 19. Between these collars, and loosely free to revolve on the plunger, is a circuit closing element consisting of a disc 20. The collars are so spaced as to permit the disc the freedom to tilt in any direction, and the internal diameter of the sleeve is enlarged toward the bottom in order to afford the plunger a slight wobble.

The disc or circuit closing element 20 is formed of stiff insulation (non-conductive) material, and inlaid in the upper face of this disc is a ring 21 (see Figs. 4 and 5) of conductive material. The mean diameter of this ring equals the distance between the axes of the posts 14.

Pivoted to the yoke as at 22 and again at the lower end of the plunger 18 as at 23, is an arm 24 which carries a float 25 at its free end. The arm is, in effect, a lever to which reciprocal movement of the plunger 18, and hence the disc 20, are responsive. The arm may be extensible by means of a telescoping structure as shown.

The members which reside within the reservoir, namely, the float 25 and the yoke 17, are less in girth than the diameter of the reservoir filling opening, and therefore the assembly may be easily inserted by introducing it float first in an arcuate path as illustrated in Fig. 2 and indicated by the arrow thereon. The cup is then screwed into place, and because of the swivel the float assembly will not turn with the cup. Obviously the device may be as easily removed for recharging the braking system.

In operation, assuming that the level of the fluid in the reservoir has fallen appreciably below maximum but not to the danger point, the float having also fallen has elevated the plunger 18 and the disc 20, the ring 21 of the latter into contact with the posts 14, the circuit becomes closed and the alarm energized.

The disc 20 is loosely connected to the plunger, and therefore tiltable, in order to assure even contact with both posts should the axis of the plunger be out of parallel with that of the cup,

or with that of the posts, or should there happen to be disparities in the position of the posts.

I claim:

1. In a fluid level controlled switch, a cup having a threaded base portion, a pair of terminal posts extending into the cup through a non-conductive cup closure, a swivel comprising a sleeve journaled in said base portion and a yoke beneath the sleeve, a plunger reciprocally operable in the sleeve, a circuit closing element in the cup and loosely carried by the plunger, and an arm having buoyant means at its free end and pivoted to the yoke at one point and to the plunger at another point, said circuit closing element including a disc loosely rotatable on the plunger between a pair of collars, the space between the collars being greater than the thickness of the disc.
2. In a fluid level controlled switch, a cup having a threaded base portion, a pair of terminal posts extending into the cup through a non-conductive cup closure, a swivel including a sleeve journaled in said base portion, a plunger operable in the sleeve, a circuit closing element in the cup and loosely carried by the plunger, and buoyant means associated with the plunger for elevating the circuit closing element into contact with the terminal posts on the dropping of a fluid level, said circuit closing element including a disc loosely rotatable on the plunger between a pair of collars, the space between the collars being greater than the thickness of the disc.

ROBERT B. MACDONALD.
